Primary Examiner — Nathan M Johnston

(74) Attorney, Agent, or Firm — Manelli Selter PLLC;
 Edward Stemberger(57) **CLAIM**

The ornamental design for a helmet hanger holder, as shown and described.

DESCRIPTION

FIG. 1 is a front perspective view of a helmet hanger holder in accordance with the invention;

FIG. 2 is a rear perspective view thereof;

FIG. 3 is a front elevational view thereof;

FIG. 4 is a rear elevational view thereof;

FIG. 5 is a right side elevational view thereof;

FIG. 6 is a left side elevational view thereof;

FIG. 7 is a top plan view thereof; and,

FIG. 8 is a bottom view thereof.

The broken lines shown in the drawings illustrate structure or features that form no part of the claimed design.

1 Claim, 5 Drawing Sheets(56)
